UNITED STATES PATENT OFFICE.

SAMUEL W. HYATT, OF CONNERSVILLE, INDIANA, ASSIGNOR TO INDIANA LAMP CORPORATION, OF CONNERSVILLE, INDIANA, A CORPORATION.

ADJUSTING DEVICE.

Application filed February 2, 1926. Serial No. 85,530.

This invention pertains to an adjusting mechanism for obtaining vertical adjustment of a movable structure with respect to a fixed structure, and is particularly adaptable to 5 focusing bulbs in headlights.

The principal feature of the invention resides in a rotatable member, such as a disk, which is provided with a slot of cam-like curvature, the rotatable member being pivotally mounted to a fixed support such as the 10 back plate of a lamp casing, to be connected with a screw or suitable member of that character for rotating the same. The object to be adjusted, such as the mounting for the 15 lamp bulb, is connected with a member extending through a vertical slot in the casing so as to limit it to a given movement, and also extending through the cam-like slot in the rotatable member for varying or adjusting 20 its position in the fixed slot upon said member being rotated.

This structure permits of a simple and economical mechanism for securing a fine adjustment of a lamp bulb or similar object.

Still a further feature of the invention resides in the employment of such an adjusting or focusing device used in connection with a lamp reflector of either a hyperbola or parabola shape, which may be divided into sections so as to permit the treatment of light 30 from the reflector to be "aimed" or varied by means of the adjustment so as to obtain the prescribed lighting effect.

The full nature of the invention will be 35 understood from the accompanying drawings and the following description and claims:

In the drawings, Figure 1 is a cross section taken through the lamp structure illustrating one form of the invention. Fig. 2 is a plan view thereof taken from the rear of the casing. Fig. 3 is the same as Fig. 1, showing a modified form. Fig. 4 is the same as Fig. 2, showing a modified form of the structure shown in Fig. 3. Fig. 5 is a section taken on 40 the line 5—5 of Fig. 3.

In the drawings there is shown a lamp casing 10 in which there is fixedly mounted a reflector 11 having a lamp socket 12 slidably mounted therein for supporting a lamp bulb 13 at substantially the focal point of the reflector. The socket 12 is provided with a bracket 14 secured rigidly thereto and longitudinally of the periphery. The socket is so mounted in the reflector as to tilt therein as 50 well as freely slide longitudinally thereof,

but is prevented from rotation by reason of the engagement of the bracket 14 with a cut-out portion in the reflector, as at 15. The free end of the bracket, to the rear of the socket, is provided with screw threads into 60 which a screw bolt 16 is adapted to screw, said bolt having its ends split at 17 for providing a stop, and also having a head 18 of the usual character positioned on the exterior of the lamp casing.

Mounted on the interior of the casing and against the inner surface of the rear thereof there is an adjusting or focusing member such as the disk 19 which is keyed to the stud 20 extending through the rear of the 70 casing at the center thereof and provided with the screw head 21.

The stud 20 is surrounded by a compression spring 22 positioned intermediate the plate 19 and a washer 23, and the screw bolt 16 is likewise surrounded with a compression spring 24 mounted intermediate the free end of the bracket 14 and said disk 19. The rear of the casing is provided with a longitudinal vertical slot 25, through which said screw bolt is adapted to extend, and the rotatable adjusting member or disk 19 is provided with a cam-like slot 26 through which the screw bolt likewise extends.

In operation, it is obvious that upon turning the screw 16, the lamp socket will be caused to slide back and forth horizontally and be held in adjusted position by the spring 24, whereby the source of light contained in the bulb 13 may be positioned to the front or rear of the vertical focal plane. On the other hand, by turning the head 21 of the stud 20, the adjusting disk will be rotated 80 so as to raise or lower the screw bolt 16 by reason of the action with respect thereto of the cam-like slot 26. This has the effect of

tilting the source of light downwardly below the horizontal plane of the focal point upon the screw bolt being raised, and tilting the source of light upwardly upon the screw bolt being lowered. While the adjustment of the screw bolt 16 through the medium of its head 18 has the effect of focusing the light for obtaining substantially parallel rays on 90 the one hand, or either convergent or divergent rays on the other hand, the rotation of the stud 20 by means of its head 21 will permit of the so-called "aiming" of the beam, i. e., throwing it downwardly or upwardly, 95 as desired. If a perfect parabolic reflector is 100

105 well as freely slide longitudinally thereof, 110

employed, with the source of illumination theoretically at the focal point, it is well known that the rays of light projected thereby will be horizontal. On the other hand, if by means of the focusing adjustment through the screw head 18, the source of illumination is moved forward of the focal point, the rays of light projected by the reflector will be convergent, and if moved to the rear, will be divergent. If, through the operation of the stud head 21, the source of light is moved slightly upwardly, the principal direction of the main beam of light projected from the reflector, will be below the horizontal. Thus the beam of light projected from the lamp may be adjusted so as to obtain the desired focusing effect as well as the desired "aiming" of the principal beam, as desired, either above or below the horizontal.

As illustrated in Figs. 3 and 4, the same results were obtained through a screw head set within a narrow knob. As shown herein the socket 112 is provided with the bracket 114 having an offset end 115 extending through a suitable opening in the reflector 11. Intermediate the ends of the bracket there is a reduced space adapted to be straddled or embraced by the bifurcated end of the upright bracket 116, the upright bracket 30 being connected at its opposite end, which is bent rearwardly to a fixed support 117. The lower end of the support 117 is provided with a vertical slot 118 in which the rear end of the bracket 114 is slidably mounted.

Extending through the rear of the casing 10 there is a stud 119 having a knurled head 120, said stud being rotatably mounted therein by the bearing member 121, which also secures the bracket 117 to the rear of the casing. The end of the stud is formed in octagonal shape as at 122, or in a similar manner is keyed to a disk 123, which is caused to rotate upon the knurled head 120 being turned. Said disk is held in position 45 against the bracket 117 by a compression spring 124, and is provided with a cam-like slot 125.

Extending through the stud 119 there is a threaded screw bolt 126 having a screw head 127, said bolt being adapted to screw 50 through the bracket 116 and having spread ends for limiting the movement of said bracket in one direction.

In operation, when it is desired to move 55 the bulb 13 horizontally, the screw bolt 126 is turned through the medium of its head 127, so as to cause the bracket 116 to move back or forth and thereby causing the bracket 114 to slide longitudinally, carrying 60 the lamp socket therewith. Upon it being desired to tilt the lamp in a vertical plane, the knob 120 is turned, which causes the disk 123 to turn therewith so as to vary the vertical position of the cam-like slot 125 with 65 respect to the slot 118 in the bracket 117.

Such movement causes the rear end of the bracket 114 to slide vertically in the slot 118 as well as between the bifurcated ends of the bracket 116, thus tilting the lamp 13 in the same manner as described with respect to Fig. 1. While the adjusting device has herein been shown and described with respect to a lamp structure for focusing the bulb and "aiming" the beam of light, it may be employed in a like manner for securing various 75 adjustments with respect to other structures.

The invention claimed is:

1. The combination with a lamp casing, and a reflector mounted therein, of a socket 80 slidably mounted in said reflector for supporting a source of illumination, means for adjusting the position of said socket by slidably moving the same with respect to said reflector, a circular disc having a cam-like slot 85 therein through which said adjusting means extends, and means for pivotally mounting said disc on said casing and rotating the same for varying the position of said adjusting means and effecting a tilting movement to said socket independently of its sliding adjustment.

2. A headlight including, in combination, a reflector, a lamp socket extending through the rear end of the reflector and supported for rocking movement about a horizontal axis, means for preventing rotation of the socket with respect to the reflector, a casing having its back disposed at some distance behind the reflector and having this back provided with a vertical slot, socket tilting means including a portion fast on the socket and a second portion extending slidably through the said slot; and an adjusting member movably mounted on the said back of the casing and having a cam slot crossing the said vertical slot, through which cam slot the said second part of the socket tilting means also extends.

3. A headlight including, in combination, a reflector, a lamp socket extending through the rear end of the reflector and supported for rocking movement about a horizontal axis, means for preventing rotation of the socket with respect to the reflector, a casing having its back disposed at some distance behind the reflector and having this back provided with a vertical slot, socket tilting means including a portion fast on the socket and a second portion extending slidably through the said slot; and an adjusting member rotatably mounted on the said back and having a substantially involute slot extending across the said vertical slot and engaging upper and lower edges of the said second portion of the socket tilting means.

4. In a lamp, a reflector, a lamp socket mounted for vertical tilting movement with respect to the reflector, a tilt-effecting member extending rearwardly from the socket and having its axis parallel to that of the

- socket, a lamp body having in its back a vertical slot through which the tilt-effecting member extends and in which slot that member is vertically slideable; and an adjusting member rotatably mounted on the said back on an axis spaced vertically from that of the reflector, the adjusting member having a helical slot extending across the said vertical slot and through which the tilt-effecting member also extends, and spring means interposed between the tilt-effecting member and the adjusting member for preventing accidental rotation of the latter.
5. In a lamp, a forwardly open reflector having a perforation in its rear end, a lamp socket extending through the perforation and supported for vertical rocking movement, and socket-tilting means comprising a tilting member connected to and extending rearwardly axially of the socket, a lamp casing housing the reflector and having a back provided with a vertical slot through which the tilting member extends; an adjusting member rotatably mounted within the casing back on an axis which extends longitudinally of the reflector and which is substantially in the same medial plane with the vertical center line of the said slot; the adjusting member having a portion disposed close to the casing back and provided with a helical slot through which the tilting member also extends; and means operable from the rear of the casing for moving the adjusting member so as to vary the part of the helical slot through which the tilting member extends.
10. In a lamp, a forwardly open reflector having a perforation in its rear end, a lamp socket extending through the perforation and supported for vertical rocking movement, and socket-tilting means comprising a tilting member connected to and extending rearwardly axially of the socket, a lamp casing housing the reflector and having a back provided with a vertical slot through which the tilting member extends; an adjusting member having a portion bearing against the inner face of the casing back and having the said portion provided with a helical slot through which the tilting member also extends; and means operable from the rear of the casing for moving the adjusting member so as to vary the part of the helical slot through which the tilting member extends, the said means comprising a bolt rotatably mounted on the back of the casing and fast with respect to the adjusting member.
15. In a lamp, a forwardly open reflector having a perforation in its rear end, a lamp socket extending through the perforation and supported for vertical rocking movement, and socket-tilting means comprising a tilting member connected to and extending rearwardly axially of the socket, a lamp casing housing the reflector and having a back provided with a vertical slot through which the tilting member extends; an adjusting member having a portion bearing against the inner face of the casing back and having the said portion provided with a helical slot through which the tilting member also extends; and means operable from the rear of the casing for moving the adjusting member so as to vary the part of the helical slot through which the tilting member extends, the said means comprising a bolt rotatably mounted on the back of the casing and fast with respect to the adjusting member.
20. In a focusing lamp, a reflector, a lamp socket mounted for rocking movement with respect to the reflector, a casing including a back provided with a vertical slot and with a perforation spaced from the slot; a bolt rotatable in the said perforation and having a shank portion of non-circular section adjacent to the forward face of the said back; an adjusting member having a portion fitting the said non-circularly sectioned shank portion and having another portion bearing against the forward face of the said back, the last named portion having a cam slot 70 extending transverse of the said vertical slot, and socket tilting means including a part supported by the socket and extending rearwardly from the socket in fixed disposition with respect to the axis of the socket, the said part extending through both of the said slots.
25. In a focusing lamp, a reflector, a lamp socket mounted for rocking movement with respect to the reflector, a casing including a back provided with a vertical slot and with a perforation spaced from the slot; a bolt rotatable in the said perforation and having a shank portion of non-circular section adjacent to the forward face of the said back; an adjusting member having a portion fitting the said non-circularly sectioned shank portion and having another portion bearing against the forward face of the said back, the last named portion having a cam slot 75 extending transverse of the said vertical slot, and socket tilting means including a part supported by the socket and extending rearwardly from the socket in fixed disposition with respect to the axis of the socket, the said part extending through both of the said slots.
30. In a focusing lamp, a reflector, a lamp socket mounted for rocking movement with respect to the reflector, a casing including a back provided with a vertical slot and with a perforation spaced from the slot; a bolt rotatable in the said perforation and having a shank portion of non-circular section adjacent to the forward face of the said back; an adjusting member having a portion fitting the said non-circularly sectioned shank portion and having another portion bearing against the forward face of the said back, the last named portion having a cam slot 80 extending transverse of the said vertical slot, and socket tilting means including a part supported by the socket and extending rearwardly from the socket in fixed disposition with respect to the axis of the socket, the said part extending through both of the said slots.
35. In a focusing lamp, a reflector, a lamp socket mounted for rocking movement with respect to the reflector, a casing including a back provided with a vertical slot and with a perforation spaced from the slot; a bolt rotatable in the said perforation and having a shank portion of non-circular section adjacent to the forward face of the said back; an adjusting member having a portion fitting the said non-circularly sectioned shank portion and having another portion bearing against the forward face of the said back, the last named portion having a cam slot 85 extending transverse of the said vertical slot, and socket tilting means including a part supported by the socket and extending rearwardly from the socket in fixed disposition with respect to the axis of the socket, the said part extending through both of the said slots.
40. In a focusing lamp, a reflector, a lamp socket mounted for rocking movement with respect to the reflector, a casing including a back provided with a vertical slot and with a perforation spaced from the slot; a bolt rotatable in the said perforation and having a shank portion of non-circular section adjacent to the forward face of the said back; an adjusting member having a portion fitting the said non-circularly sectioned shank portion and having another portion bearing against the forward face of the said back, the last named portion having a cam slot 90 extending transverse of the said vertical slot, and socket tilting means including a part supported by the socket and extending rearwardly from the socket in fixed disposition with respect to the axis of the socket, the said part extending through both of the said slots.

In witness whereof, I have hereunto affixed my signature.

SAMUEL W. HYATT.
